UNITED STATES PATENT OFFICE.

WILLIAM A. CHEW, OF ATLANTIC CITY, NEW JERSEY.

LAMP LOCKING-BASE.

1,229,231.

Specification of Letters Patent. Patented June 12, 1917.

Application filed October 23, 1916. Serial No. 127,240.

To all whom it may concern:

Be it known that I, WILLIAM A. CHEW, a citizen of the United States, residing at Atlantic City, in the county of Atlantic and 5 State of New Jersey, have invented a new and useful Lamp Locking-Base, of which the following is a specification.

The object of the invention is to provide a lamp base adapted for use in connection 10 with incandescent lights of the type wherein it is desired to permit a facile seating of the base in a lamp socket, but to prevent a malicious removal of the base, wherein increased certainty of operation may be secured. It has been found in practice, with 15 the type of lamp bases indicated, that if the seating thereof in the socket has been forcible, there is frequently sufficient friction secured between the relatively movable parts of the base to permit of backing the exterior shell out of the socket without 20 injury to the lead wires or filament; and moreover that with present commercial types, the use of spring pawls for imparting motion from the lamp base to the shell, both in seating and unseating the latter in the socket, involves the risk of the backing pawls engaging the wall of the shell before 25 the lead wire or filament has been broken, thus enabling the operator to unseat the shell without permitting the parts of the device to perform their intended functions.

It is the purpose of this invention to provide such means for communicating motion 30 from the base to the shell as to guard against this improper manipulation and insure the destruction of the lead wire or filament before the unseating of the shell from the socket can be accomplished.

With the foregoing and other objects in view which will appear as the description proceeds, the invention resides in the combination and arrangement of parts and in the details of construction hereinafter described and claimed, it being understood 45 that changes in the precise embodiment of the invention herein disclosed, can be made within the scope of what is claimed, without departing from the spirit of the invention.

In the drawings:—

Figure 1 is a side view of a lamp base structure embodying the invention.

Fig. 2 is an axial sectional view of the 55 same showing its parts in their normal or operative positions.

Fig. 3 is a similar view taken on a plane at right angles to Fig. 2 on the plane indicated by the line 3—3 of Fig. 2.

Fig. 4 is a transverse sectional view taken 60 on the plane indicated by the line 4—4 of Fig. 2.

Fig. 5 is a transverse sectional view taken 65 on the plane indicated by the line 5—5 of Fig. 3.

In the construction shown, the base proper is indicated by 10 and is arranged within a shell 11 having the common threaded surface for engagement with a lamp socket of the ordinary type (not shown). The shell 70 11 has the usual porcelain cap 12 which is connected with the base 10 by means of a tubular thimble 13, said thimble forming the passage through which extends the lead wire 75 of a filament 14, which should be broken in attempting to unseat the lamp from its socket.

In the construction illustrated, the thimble 13 is provided at its inner end with a flange 14' having outwardly projecting spurs 80 15, which enter an insulating washer 16 held to the base 10, as shown at 17. The washer 16 preferably is made of soft paper or other material adapted to perform the function of an insulator but capable of being torn 85 or destroyed readily when an attempt is made to remove the base 10 outwardly from the shell 11. At its other end, the thimble 13 is flanged or swaged as at 18 over a cupped washer 19, which is thus interposed 90 between the flange 18 of the thimble and a contact member 20. This contact member 20 preferably consists of a small blank of copper or similar metal having an eye 21 through which the thimble 13 projects, and 95 a contact cap 22 connected by an integral, bendable, reduced neck 23 with the body portion of the contact member. The construction described provides for the free swiveling of the contact cap 22 with respect 100 to the shell 11, and after the lead wire 14 has been carried through the thimble 13, subsequent to the sealing of the bulb in the base 10, and has been soldered to the washer 19, the contact cap 22 should be pressed 105 down over the washer and over the end of the thimble, as shown in Fig. 3, to form the electrical contact in the socket. The base 10 may then be turned or revolved with reference to the shell 11, regardless of the force 110 with which the shell may have been screwed into the socket, without tending to impart

reverse motion to the shell in the direction necessary to unscrew it from the socket. In order to remove the shell 11 from the socket, it is necessary first to draw outwardly upon the base 10, with a force sufficient to break the washer 16 and the lead wire 14 as herein-after fully explained.

The means for communicating clock-wise or seating movement from the base 10 to the shell 11 consists of single tongue spring pawls 43, two of which are illustrated, secured in any suitable manner to the base 10 and projecting outwardly therefrom along substantially tangential lines, and a stop or inward projection 24 on the shell in the path of said pawls when the base is in its normal position with relation to the shell as shown in Fig. 2. The stop or projection 24 is provided with an abrupt side for terminal engagement by one of the pawls 43 and with an inclined or beveled opposite side whereby reverse or contra-clockwise movement of the base 10 will cause the pawls to slip over the stop or projection without imparting movement to the shell 11.

The means for communicating the contra-clock-wise or unseating movement from the base 10 to the shell 11 consists of a projection 25 extending exteriorly from the base 10 for engagement with a stop or inward projection 26 in the shell. In order to bring the unseating members into a transverse plane which will permit of their engagement, the base 10 must be moved axially within the shell 11 a distance sufficient to break the insulating washer 16 and the lead wire 14, or stated differently, to the position indicated in Fig. 3. In other words, when the seating means consisting of the pawls 43 and the stop or projection 24 are in the same transverse plane, permitting of engagement thereof for the purpose of seating the shell 11 in the socket, the unseating means consisting of the projections 25 and 26 are out of alignment or are in different transverse planes, and are held out of alignment by the engagement between the thimble 13 and the insulating washer 16, and the movement of the base 10 to bring said unseating means into operative relation destroys the usefulness of the lamp.

Having thus described the invention, what is claimed is:—

1. An electric lamp having a base comprising an outer socket engaging shell, and an inner bulb carrying shell, a swivel connection between said shells including a frangible washer adapted to be fractured by relative outward movement of said parts, and seating and unseating means, the members of which are carried respectively by said shells, and the members of one means being cut out of operative relation when the members of the other means are in operative relation.

2. An electric lamp base comprising an outer socket engaging shell, and an inner bulb carrying shell, a frangible insulating washer carried by the inner shell, a thimble connecting said washer with the outer shell, and forming a swivel connection between the same, and seating and unseating means, the members of each of which are carried respectively by the inner and outer shells, the members of one of said means being out of operative relation when the members of the other means are in operative relation.

3. An electric lamp base comprising an outer socket engaging shell and an inner bulb carrying shell, a swivel connection between said shells including a thimble, terminally detachable from one of said shells by longitudinal movement of the inner shell, and seating and unseating means, the members of each of which are carried respectively by the inner and outer shells, the members of one of said means being out of operative relation when the members of the other means are in operative relation.

4. An electric lamp base comprising an outer socket engaging shell and an inner bulb carrying shell capable of relative rotary and outward movements, a swivel connection between said shells to normally prevent relative axial movement thereof, and terminally detachable from one of said shells by forcible outward movement, and seating and unseating means, the members of each of which are carried respectively by the inner and outer shells, the members of one of said means being out of operative relation when the members of the other means are in operative relation.

5. An electric lamp base comprising an outer socket engaging shell and an inner bulb carrying shell capable of relative rotary and outward movements, a frangible washer seated in the inner shell, a thimble engaging said washer and revolvably mounted in the other shell, and a contact cap swiveled upon the outer shell and covering the exposed end of said thimble, and seating and unseating means, the members of each of which are carried respectively by the inner and outer shells, the members of one of said means being out of operative relation when the members of the other means are in operative relation.

6. An electric lamp base comprising an outer socket engaging shell and an inner bulb carrying shell adapted for relative rotary and outward movements, a swivel connection between said shells including a thimble detachably engaged with the inner shell and having one lead wire attached thereto, a contact cap swiveled upon said thimble and covering the exposed end thereof, and seating and unseating means, the members of each of which are carried respectively by the inner and outer shells, the

members of one of said means being out of operative relation when the members of the other means are in operative relation.

7. An electric lamp base comprising an outer socket engaging shell and an inner bulb carrying shell adapted for relative rotary and outward movements, a swivel connection between said shells including a thimble terminally seated respectively thereon, and having one of the lead wires connected therewith, a contact cap having an eye loosely receiving the outer end of said thimble, and also having a contact member for covering the exposed end of said thimble, and seating and unseating means, the members of each of which are carried respectively by the inner and outer shells, the members of one of said means being out of operative relation when the members of the other means are in operative relation.

8. An electric lamp comprising an exterior socket engaging shell and an inner bulb carrying shell adapted for relative rotary and outward movements, a swivel connection between said shells including a thimble having a flanged outer extremity, a contact cap covering the exposed end of said thimble, and having an eye loosely engaging the thimble, a cupped washer interposed between said eye and the flanged extremity of the thimble, and having a lead wire at-

tached thereto, and seating and unseating means, the members of each of which are carried respectively by the inner and outer shells, the members of one of said means being out of operative relation when the members of the other means are in operative relation.

9. An electric lamp base comprising an outer socket engaging shell, and an inner bulb carrying shell adapted for relative rotary and outward movements, a swivel connection between said shells including a thimble detachably engaging one of said shells, seating means consisting of a single tongue pawl carried by one of said shells, and a beveled projection on the other shell normally arranged in the path of said pawl, and unseating means consisting of outward and inward projections respectively from the inner and outer shells, and normally arranged in different transverse planes and adapted to be disposed in a common transverse plane by relative outward movement of the shells.

In testimony that I claim the foregoing as my own, I have hereto affixed my signature in the presence of two witnesses.
